UNITED STATES PATENT OFFICE.

WILLIAM ALBERT RUDDELL, OF ASBURY PARK, NEW JERSEY.

GLOVE PATTERN.

1,427,419.

Specification of Letters Patent. Patented Aug. 29, 1922.

Application filed July 6, 1921. Serial No. 482,813.

To all whom it may concern:

Be it known that I, WILLIAM A. RUDDELL, a citizen of the United States, residing at Asbury Park, in the county of Monmouth 5 and State of New Jersey, have invented certain new and useful Improvements in Glove Patterns, of which the following is a specification.

This invention relates to improvements 10 in garment patterns and more especially to an improved pattern assemblage by the use of which gloves and other hand coverings may be accurately cut from any desired and suitable material and the component parts 15 assembled and united without the exercise of any particular skill, so that one supplied with the pattern may produce any desired number of gloves for personal use or may engage in the manufacture of gloves on a 20 commercial basis.

Another object of the invention is to produce a pattern assemblage in which the component parts will bear a novel arrangement of symbols indicating the manner in which 25 blanks cut by the aid of the pattern parts are to be assembled and united to produce the completed glove or other hand covering.

In the accompanying drawings:

Figure 1 is a plan view of the main or 30 body pattern part of the assemblage;

Figure 2 is a plan view of the thumb part of the pattern assemblage;

Figure 3 is a group view illustrating in 35 plan pattern parts which bear relation to the first finger, second finger and little finger;

Figure 4 is a plan view of the pattern part to be employed in producing a blank for a gauntlet cuff;

Figure 5 is a similar view illustrating another pattern part for producing a gauntlet cuff blank;

Figure 6 is a plan view illustrating a pattern part for the production of a wrist blank;

Figure 7 is a similar view illustrating another pattern part for the production of a wrist blank;

Figure 8 is a plan view illustrating a pattern part for the production of a sleeve protector blank to be employed in connection with the hand covering proper.

The pattern assemblage illustrated in the drawings is designed for use in cutting out 5 a plurality of blanks, from any desired ma-

terial, which blanks are to be united to produce a hand covering of the glove type but it will be understood, particularly after a consideration of the specific description of this embodiment of the invention which is 60 to follow, that the principles of the invention may be carried out in the production of mittens, gloves having component parts or contours other than those indicated by the contours of the pattern parts shown in 65 the drawings, and in fact hand coverings of any and all designs and regardless of the use to which they are to be put.

In the drawings, the main pattern part, which is illustrated in Figure 1, is indicated in general by the numeral 1, and it like all of the other pattern parts illustrated in the other figures of the drawings, may be formed from paper or any other sheet material which it is found desirable to employ. The main pattern part 1 comprises a palm portion 2, an index finger portion 3, a first finger portion 4, a second finger portion 5, a little finger portion 6, and a thumb portion 7, the finger portions 4, 5 and 6 being integrally joined with the upper part of the palm portion 2 and being mutually separated by incisions 8 and 9. The first finger portion 4 is likewise separated from the index finger by an incision 10. The finger portions 4, 5 and 6 are of a marginal contour and dimensions to provide, in the blank cut from the pattern 1, a covering for the inner sides of the first, second and little fingers. The index finger portion 3 80 on the other hand is of a width such that the blank part corresponding thereto, when properly folded and marginally stitched, will provide the complete stall for the index finger, this index finger portion 3 at its 85 upper margin being scalloped at an intermediate point, as indicated by the numeral 11, so that the rounded marginal portions 12 and 13 lying at opposite sides of the scallop, will define the contour of the tip of the 90 index finger when the blank cut from the pattern is properly stitched. That lateral margin of the pattern part 1 which defines one boundary of the index finger portion 3, is cut in as indicated at 14 substantially at 95 a point corresponding to the base of the index finger below which portion the margin is straight as indicated by the numeral 15. The lower portion of the pattern part 1 corresponds to the wrist line of a blank cut 100

105

110

therefrom, as indicated by the numeral 16, and the thumb portion 7 is defined by incisions 17 and 18 which extend inwardly from the margin 16 along lines curving toward each other, the inner end of the incision 17 being located approximately vertically in alinement below the inner end of the incision 10, and the inner end of the incision 18 being located approximately in vertical alinement below the scallop 11. Likewise the inner ends of the incisions 17 and 18 terminate adjacent the transverse median line of the palm portion 2 of the pattern part 1. The other lateral margin of the pattern part 1, which is indicated by the numeral 19, is straight and parallel to the margin 15 and defines one lateral edge of the palm portion 2 and one lateral edge of the little finger portion 6.

20 As heretofore stated the invention contemplates providing the pattern parts with indicating symbols so arranged as to indicate the precise manner in which the blanks cut by the aid of these parts are to be assembled and stitched together. Thus in the case of the pattern part 1, symbols comprising the letters of the alphabet are printed or otherwise marked upon one or both faces of the said pattern part and by reference to 25 Figure 1 it will be observed that the letter A is located upon the face of the palm portion 2 near the wrist line 16 and at one side of and close to the point where the incision 18 opens through the said wrist line or margin, 30 this reference character, being the first letter in the alphabet, indicating the starting point for the stitching operation, and preferably there is printed upon the face of the blank in juxtaposition to the letter a legend such for example as "Start to sew here," as indicated by the numeral 20. The letter B is located at the inner end of the incision 18, 35 C at the tip end of the thumb portion 7, D at the inner end of the incision 17, and E at one side of and adjacent to the point where the incision 17 opens through the margin 16. The letter F is repeated at intervals upon the face of the pattern part 1 along the margin 15 and incut margin 14, and the letter G 40 is repeated at intervals along the margin 19. The letter J is repeated upon the face of the blank at intervals along the curved marginal portions 12 and 13 and at the point of the scallop of the index finger 45 3, and the letters L, N and O are located at the tips of the finger portions 4, 5 and 6 respectively.

The index finger portion 3, and the first, second and little finger portions 4, 5 and 6, 50 are indicated individually by appropriate legends, as is also the thumb portion 7, suitably identifying these portions of the pattern part.

The pattern part shown in Figure 1 may 55 be employed, in conjunction with other pat-

tern parts to be presently described, in cutting out the blanks which are to comprise a glove having a closed wrist but in order to adapt the pattern part 1 for use where a glove is to be produced with an open wrist 70 designed to be closed by one of more buttons or clasps, there is printed or otherwise indicated, as at 21, upon the face of the pattern 1, a line 21 along which an incision may be made in the palm portion of the blank being 75 cut extending inwardly from the wrist line or margin 16, and the said palm portion of the pattern part may bear, in juxtaposition to this line, any appropriate legend such for example as "Only cut or sew at this line 80 when button or clasp gloves are desired."

Figure 2 of the drawings illustrates in plan a pattern part which is indicated by the numeral 22 and which is to be employed in cutting out a blank which when assembled 85 with and united to the blank cut by the use of the pattern part 1, will complete the thumb stall of the glove or other hand covering and close the opening vacated by the part of the second-mentioned blank corresponding to the thumb portion 7 of the pattern 1. The pattern part 22 has a basal marginal portion 23 which is straight and the pattern part has other lateral marginal portions 24 and 25 which extend from the ends of the 90 marginal portion 23 along diverging lines to a point approximately at the transverse middle of the pattern part 22 where they join other marginal portions 26 and 27 respectively which latter converge and are 100 joined at their relatively adjacent ends by a curved marginal portion 28 defining the tip of the thumb blank to be cut, the curvature of this tip corresponding to the curvature of the tip of the thumb portion 7 of the pattern part 1. Symbols are printed upon the face of the pattern part 22 preferably in the following order:—The letter A at the juncture of the marginal portions 23 and 24; the letter B at the juncture of the marginal portions 24 and 26; the letter C in juxtaposition to the marginal portion 28; the letter D at the juncture of the marginal portions 25 and 27; and, the letter E at the juncture of the marginal portions 23 and 25. 110

Figure 3 of the drawings illustrates three other pattern parts representative of the first finger, second finger, and little finger, and indicated respectively by the numerals 29, 30 and 31 and each bearing a suitable indicating legend. The pattern part 29 represents the first finger and which is a companion part to the portion 4 of the pattern part 1, and comprises a relatively broad upper portion 32 and a relatively narrow 120 lower portion 33, the portion 32 at its tip having a curvilinear margin 34, and the lateral margins or edges of the pattern part as a whole being cut in along curved lines, as at 35, at the juncture of the portions 32 and 130

33. The portion 32 is of a length substantially equivalent to the portion 4 of the pattern part 1 but is broader than said portion, and the portion 33 is of a length substantially equivalent to the distance between the base of the portion 4 and the wrist line or lower margin 16 of the said pattern part 1.

The pattern part 29, like the pattern parts 1 and 22, is provided with designating symbols preferably as follows:— The letter F is repeated at intervals along one lateral margin of the portion 33 from the lower end of the said portion to its juncture with the portion 32; the letter G is repeated at intervals in the like manner and for a like distance along the other lateral margin of the portion 33; and, the letter L is located at the tip of the portion 32 in juxtaposition to the margin 34.

The pattern part 30 is very similar in its marginal contour to the pattern part 29 and comprises a relatively broad upper portion 36 and a narrow lower portion 37, the lateral margins of the pattern part being cut in at the juncture of the portions 36 and 37, along curved lines, as indicated by the numerals 38 and 39, the curvilinear marginal portion 38 extending to substantially the same distance above the lower end of the portion 37 as the marginal portions 35 of the pattern part 29, and the marginal portions 39 terminating at a lower point.

The pattern part 30 bears upon its face guiding symbols preferably as follows:— The letter G is repeated at intervals along that lateral margin of the blank of which the portion 38 constitutes a part and from the lower end of the blank to the juncture of the parts 36 and 37; the letter H is similarly repeated at intervals along the opposite margin of the blank; and, the letter N is located in juxtaposition to the tip of the portion 36.

The pattern part 31 comprises an upper relatively broad portion 40 and a narrow lower portion 41, one lateral edge of this pattern part being substantially straight throughout its entire length and indicated by the numeral 42 and the other lateral edge being cut in along a curved line, as at 43, at the juncture of the portions 40 and 41 and to a degree and in a location corresponding to the cut in edge portion 39 of the pattern part 30. On this pattern part the letter H is repeated at intervals along the last-mentioned lateral margin of the part from the lower end of the portion 41 to the upper end of the cut in marginal portion 43; the letter I is repeated at intervals throughout the entire length of the straight margin 42; and, the letter O is located in juxtaposition to the tip of the portion 40, the tip of this portion as well as that of the portion 36 of the part 30 being of curvilinear form. The pattern parts 30 and 31 respectively constitute companion parts for the portions 5 and

6 of the pattern part 1, and like the pattern part 29 and its associated portion 4, the broader upper portions of the said pattern parts 30 and 31 correspond in length substantially to the length of the respective portions 5 and 6, their lower portions being of a length substantially equal to the distance between the lower ends of the portions 5 and 6 of the pattern part 1 and the margin 16 of said part.

In the use of those parts of the pattern assemblage which have been thus far described, blanks are cut by the aid of these parts, in any convenient manner, from the material of which the glove or other hand covering is to be made, and after the blanks have been cut they are united in a manner which will now be explained, and for the sake of convenience reference will be had to the blanks as though they bear the designating letters peculiar to the pattern parts by the aid of which they were cut. The thumb portion of the blank cut by the aid of the pattern part 1 is folded back on a line extending between the points D and B, and the thumb blank cut by the aid of the pattern part 22 is then associated with the first-mentioned blank in a position inverted with relation to the position of the pattern part 22 illustrated in Figure 2 and with the corners adjacent the letters A upon the two blanks in registration, and stitching is run along the margins of the blanks from the point A to the point B. Next the blank corresponding to the pattern part 22 is united to the margin of the thumb portion of the blank corresponding to the thumb portion of the pattern part 1 along the marginal line indicated successively by the letters B, C and D, and finally the blanks are stitched together along the marginal line from D to E. Thus the space vacated by the thumb portion of the blank cut by the aid of the pattern part 1 is closed and the thumb stall is completed.

The blank cut by the aid of the pattern part 1 is then overturned along the line extending substantially from the scallop 11 to the inner end of the incision 18, and the curvilinear edge portions 12 and 13 of the portion 3 of the blank are united by a line of stitching, the line of stitching being continued downwardly along the lateral margins of the folded portion 3 so as to close and complete the stall for the index finger. The marginal portion 15 of the blank along the line of the letter F is at this time unattached, and now the blank cut by the aid of the pattern part 29 is applied to the partly finished article by bringing the marginal portion thereof defined by the letters F into registration with the marginal portion 15 defined by the corresponding letters, and a line of stitching is run along these marginal portions. Also the upper portion 32 of the blank cut

4
by the aid of the part 29 is united from F to L and from L to G marginally to the portion 4 of the blank cut by the aid of the pattern part 1. Next, the blank cut by the aid of the 5 part 30 is assembled with and united along the marginal portion indicated by the letters G to the corresponding marginal portion of the blank cut by the aid of the pattern part 29, and the blank cut by the aid of the 10 pattern part 30 is then united from G to N and from N to H marginally to the part 5 of the blank cut by the aid of the pattern part 1. Next, the blank cut by the aid of the pattern part 31 is united along the marginal 15 portion designated by the letters H to the corresponding marginal portion of the blank cut by the aid of the pattern part 30 and similarly united marginally from H to O and from O to I and throughout the margin 42 of the portion 6 and the margin 19 of the blank cut by the aid of the pattern part 1.

If the hand covering is to have a closed wrist, it is completed by the method of procedure above outlined except for the provision of a wrist or cuff portion. If it is to be open and adapted to be closed by buttons or clasps, then an incision is made along the line 21 of the blank cut by the aid of the 25 pattern part 1, the edges of the incision are suitably finished, and the buttons or clasps are applied. Figures 4, 5, 6 and 7 illustrate various pattern parts from which wrist bands or cuffs may be prepared. For example Figure 4 illustrates a pattern part designated in general by the numeral 44 and by the use of which two blanks are to be cut which blanks may be stitched together along either lateral edge 45 and then united 30 along the curvilinear lower edge 46 to the marginal portion 16 of the partly completed glove prepared as above described. The pattern part 44 may be provided with a suitable identifying legend, and directions 35 for its use may be printed upon either or both sides thereof. Also a suitable legend 47 for its use may be printed upon either or both sides thereof. Also a suitable legend 48, as for example "Attach to glove here" 45 may be printed adjacent the margin 46, and instructions as to seaming or over-edging 50 may be printed adjacent the opposite margin. A different type of gauntlet cuff pattern part is illustrated in Figure 5 and indicated in general by the numeral 49 and as will be evidenced by a reference to said 55 figure, bears legends and instructions similar to those upon the pattern part 4. A wrist band pattern part is illustrated in Figure 6 and indicated in general by the numeral 50 and likewise bears printed instructions and legends similar to those upon the pattern parts 44 and 49. Also this pattern part 50 may be printed with an incision indicating line 51 accompanied by suitable instructions or a legend, indicating 60 the point at which the incision is to be made

in the blank cut from the part, and a button or clasp is to be employed. As the use of the blanks cut by the aid of the pattern parts 44, 49 50 and 52 is obvious, it is thought that further description is un- 70 necessary.

It will be understood that the lower portion of the part 3 and the lower portions 33, 37 and 41 of the pattern parts 29, 30 and 31 are to constitute the back of the hand covering in the blanks cut by the aid of these parts. 75

Figure 8 of the drawings illustrates one of a pair of pattern parts, indicated by the numeral 53, which is to be employed in cutting 80 blanks from which a sleeve protector is to be produced, this protector being employed in connection with the hand covering proper by being united at one end to the wrist portion of the said covering as will be readily 85 understood. This pattern part 53 comprises a relatively broad upper portion 54 and a narrower lower end portion 55, the pattern part 90 having a straight longitudinal edge 56, upper and lower end edges 57 and 58 respectively which extend at right angles to the edge 56 and are straight, and another longitudinal or lateral edge which is indicated by the numeral 59 and which is extended diagonally with relation to the other edges of the 95 blank and slightly curved throughout its length. Upon its face the pattern part will bear, near the edge 58, a suitable legend indicating that this edge portion is to be united to the glove or other hand covering, this 100 legend being indicated by the numeral 60. In like manner the pattern part bears upon its face, near its edge 57, a legend 61 indicating the manner in which this edge portion of the corresponding blank cut from the pattern is to be finished and provided with a closing means whereby it may be held about the forearm of the wearer of the hand covering. 105

Other directions or legends as indicated by 110 the numerals 62 and 63 may likewise be printed upon the face of the pattern part near the edges 56 and 59 respectively.

Having thus described the invention, what is claimed as new is:— 115

1. A glove pattern comprising a plurality of parts having the marginal contours of the component blank members of the glove which they represent and provided at intervals adjacent their margins with symbols 120 having an established sequence and indicative of the manner in which the members cut by the aid of the pattern parts are to be assembled and their margins progressively united to complete the glove. 125

2. A pattern for a hand covering comprising a plurality of parts having the marginal contours of the component members of the hand covering which they represent, and provided at intervals adjacent their mar- 130

gins with symbols indicative of the manner in which members cut by the aid of the pattern parts are to be assembled and their margins progressively united to complete the 5 hand covering.

3. A pattern for a hand covering comprising a plurality of parts having the marginal contours of the component members of the hand covering which they represent, the 10 parts being provided marginally at predetermined points with corresponding symbols having an established known sequence and therefore indicative of the manner in which the members cut by the aid of the pattern 15 parts are to be assembled and their margins progressively united to complete the hand covering.

4. A pattern for a hand covering comprising a plurality of parts having the marginal 20 contours of the component members of the hand covering which they represent, one of said pattern parts representing the index finger stall complete, the palm portion of the hand covering, and portions of the

thumb, first finger, second finger and little 25 finger stalls, and other pattern parts representing the other portions of the thumb, first finger, second finger and little finger stalls.

5. A pattern for a hand covering comprising a plurality of parts having the marginal 30 contours of the component members of the hand covering which they represent, one of said pattern parts representing the index finger stall complete, the palm portion of the band covering, and portions of the 35 thumb, first finger, second finger and little finger stalls, and other pattern parts representing the other portions of the thumb, first finger, second finger and little finger stalls, the first-mentioned pattern part having an 40 indicated incision extending from its wrist line to indicate where an incision is to be made in the wrist portion of the completed article if the same is to be of the open-wrist type. 45

In testimony whereof I affix my signature.

WILLIAM ALBERT RUDDELL. [L. S.]
